(57) **CLAIM**

The ornamental design for a toilet tool holder, as shown and described.

DESCRIPTION

FIG. 1 is a perspective view of a toilet tool holder of the present invention, showing a tool stored within the holder; FIG. 2 is another perspective view of the holder of the present invention;

FIG. 3 is a front elevation view of the holder of FIG. 2;

FIG. 4 is a rear elevation view of the holder of FIG. 2;

FIG. 5 is side elevation view of the holder of FIG. 2;

FIG. 6 is an opposing side elevation view of the holder of FIG. 5;

FIG. 7 is a bottom plan view of the holder of FIG. 2; and, FIG. 8 is a top plan view of the holder of FIG. 2.

The broken lines shown in the Figures are for illustrative purposes only and form no part of the claimed design.
